UNITED STATES PATENT OFFICE.

ONESIME HEBERT DI LE COMPTE, OF OKLAHOMA, OKLAHOMA, ASSIGNOR TO UNIVERSAL CAR AND HOSE COUPLER COMPANY, OF OKLAHOMA, OKLAHOMA, A CORPORATION OF ARIZONA.

CAR-CO尤LING KNUCKLE.

1,421,421.

Specification of Letters Patent.

Patented July 4, 1922.

Application filed December 16, 1919. Serial No. 345,315.

To all whom it may concern:

Be it known that I, ONESIME HEBERT DI LE COMPTE, citizen of the United States, residing at Oklahoma city, in the county of Oklahoma and State of Oklahoma, have invented certain new and useful Improvements in Car-Coupling Knuckles; and I do hereby declare the following to be a full, clear, and exact description of the invention, such as will enable others skilled in the art to which it appertains to make and use the same.

This invention is an improvement in the construction of a coupling of the type shown in my Patent No. 1,363,973 granted December 28th, 1920. In the coupler shown and described in the said prior application two counterpart coupler heads are designed to be aligned with their front faces in close and rigid contact, and interlocked by means of pivoted knuckles, one carried on each coupler head, said knuckles having offset shoulders on their outer sides near their forward ends each of said shoulders being adapted to engage behind an abutment formed in the companion coupler head. In the prior coupler the shoulder on the outer side of a knuckle is at right angles to an abutment surface which is adapted to contact with the inner face of the chamber in the head, and when in interlocked position the face of the shoulder which engages the said abutment is designed to be substantially perpendicular to the line of draft through the couplers.

The object of this invention is to compensate for wear in a coupler of the type indicated in order to maintain a tight and close connection between the abutting car coupler heads after they have been interlocked. In car couplers of the said type looseness or lost motion is objectionable not only because when this looseness occurs the rapidity of wear rapidly increases, but also because of the difficulty in automatically connecting and maintaining connections between train and other pipe connections and in connecting and maintaining connections between electric train circuits on the coupled cars when lost motion exists.

In the accompanying drawings:

Figure 1 is a horizontal section through two interlocked counterpart coupling heads exposing the interior mechanism;

Figure 2 is a detail of one of the knuckles.

Numerals 2 and 2' indicate, respectively, 55 hollow coupling heads which are counterparts. 3 and 3' designate knuckles one pivoted in each end. 4 and 4' designate abutments formed respectively in the said counterpart couplers, the abutments in each head 60 being located on the side opposite that on which the knuckle 3 or 3' is pivoted. 5 or 5' indicates a plane surface on the outer side of the knuckle adapted to lie flush against the inner surface of the chamber 65 within the hollow coupling head when the knuckle is projected outward in engaging position to the fullest extent possible. 6 or 6' represents a shoulder adapted to engage behind the abutments 4 or 4', respectively, in a mating coupler.

Each knuckle is provided with an ear 7 having a perforation 8 through which passes a pintle or pin 9, said pin 9 passing also into a coupling head so as to hinge the 75 knuckle to the head. As shown, the ear 7 projects through an opening 10 in the side of the coupling head, and the front of said ear is in close relation to the rear wall of said opening so that the pull or draft on a 80 knuckle may be taken up in part or wholly by the wall of the head and relieve strain upon the pin 9. By reference to Figure 1 it will be seen that the distance between the center of the pivot pin 9 and the outer portion of the surface of the shoulder 6 or 6' 85 is slightly greater than the distance from the center of said pivot pin to the inner portion of said shoulder 6 or 6', and that said shoulder 6 or 6' forms a surface which makes 90 an oblique angle with the radii which intersect it. In other words, the surface 6 or 6' forms an angle greater than 90° with a line drawn from the center of the pin to substantially any point on said surface on the 95 outer side of said line. The distance between the center of pin 9 and the front surface 11 of the coupler plus the distance from said surface 11 to the abutment 4 or 4' is slightly less than the radial distance from 100 the center of the pin 9 to the outer portion of said surface 6 or 6' and slightly greater than the radial distance from the center of said pin to the inner portion of said surface 6 or 6'. By this construction it will 105 be apparent that when the two coupler heads are brought into engagement and the knuckles caused or allowed to swing out-

ward, the surface 6 and 6' will engage the abutments 4, 4' with a cam or wedging action tending to keep the front faces of the coupling heads in close contact. The result of this is that as the abutments 4, 4' or surfaces 6, 6' wear, all wear will be taken up by the increasing outward movement of said knuckles. As shown, the surfaces 5, 5' extend in such a direction and the surfaces 6, 6' are of such a length as to allow of considerable automatic adjustment before the surfaces 5, 5' contact with the inner faces of the chambers within the coupling heads.

The draw bars are represented by 12 and 15 12' and the coupling pins by numerals 13 and 13'. 14, 14' represent pivoted dogs adapted to be moved manually or otherwise for the purpose of releasing a knuckle from engagement with the shoulder 4 or 4'.

20 In the particular coupling shown pressing the dog against the outer side of one knuckle will cause said knuckle to release the companion knuckle, the point 15 or 15' on the inner side of the outer portion of the knuckle 25 engaging with a tripping toe 16 or 16' on the knuckle of a companion coupler.

Each knuckle is constantly urged outward by means of a spring pressed plunger 17 or 17' seated in a cavity in the rear portion of 30 each knuckle, said plunger bearing against an abutment surface at the rear of the chamber within the coupling head.

Numerals 20, 20' indicate a rigid hook 35 projecting forward from each coupler head which adapts said coupler to be used in connection with a mating coupler of the Janney type.

Of the parts described the improvements for which I seek a patent relate to the modification of the knuckle described. The detail structure in which my improvement consists is diagrammatically indicated in Figure 2, where the relative inclinations of the surfaces 5 and 6 with respect to the prior known devices of the same type is clearly indicated by solid and dotted lines in comparison, the pivotal point and other features of construction being identical with the said construction over which my present invention is designed as an improvement. 50

Having described my invention in such manner as to enable those skilled in the art to make and use the same what I claim and desire to secure by Letters Patent of the United States is as follows: 55

In a car coupler, a hollow coupling head having an open front, a coupling knuckle pivoted to the head at one side of the longitudinal axis thereof and projecting forward so as to protrude from within said head, 60 said knuckle having on the outer side of the protruding portion a shoulder adapted to engage an abutment on a companion coupling head, the engaging surface of said shoulder being disposed at such an angle to the longitudinal axis of the coupler, when said surface is in position to engage the said abutment of a companion coupler, that further outward movement of the knuckle causes said surface to exert a camming action upon the abutment tending to take up wear and lost motion. 70

In testimony whereof I affix my signature.
ONESIME HEBERT dit LE COMPTE.
